UNITED STATES PATENT OFFICE.

ERWIN FALKENTHAL, OF BERLIN-DAHLEM, GERMANY.

PROCESS AND APPARATUS FOR MIXING GASES.

Original application filed October 4, 1923, Serial No. 666,608, and in Germany April 23, 1921. Divided and this application filed December 18, 1924. Serial No. 756,745.

This patent is a division of my application Ser. No. 666,608 filed Oct. 4, 1923.

This invention relates to mixing process and apparatus for mixing gases, as for instance ignition gases for combustion engines, together. The object of the invention is a mixing apparatus of a novel kind for effectuating a thorough mixing of gases, the latter being accomplished by a particular 10 construction and arrangement of one or more grids placed in a casing so as to divide the same into two or more compartments through which the unmixed and mixed gases are conducted. Each grid is constructed so 15 as to produce a peculiar effect which consists in its causing the gas passing through it to be divided up at the rear side of the grid into numerous whirls wherein the mixing process takes place. To this end the 20 grid is formed of a thin sheet preferably of metal which has a thickness about equal to drawing-paper thickness, namely 0.03 to 1.00 mm. and provided with as many regular openings as possible, which are equally 25 sized and have a smallest diameter of about tenfold the grid's thickness, namely 0.30 to 3 mm. An effective grid for the purpose of this invention can for example be produced by punching holes in sheet metal whilst for 30 example a web woven of round wire would be entirely ineffective. A round wire grid can be adapted for the purpose of this invention by flattening the same by rollers, to produce sharp edged meshes. It is to be 35 noted that the openings must in no way have the form of channels whose length exceeds their diameter or of funnels whose diameter decreases towards their one end. The numerous evenly distributed and sharp-edged 40 openings produce on the rear side of the grid numerous whirl-rings, one for each opening, wherein the gases are mixed with one another and thoroughly intermingled, without a noticeable throttling effect. The 45 distance apart from each other of the openings must be such that there exists between adjacent openings an unperforated area substantially equal with the area of the adjacent openings. According to this principle as a 50 sample of disposition in the case of slit-formed and parallel disposed openings the solid strip between each two slits must be at least as broad as the width of a slit, the said strip and the adjacent two half openings

forming in this case a so-called unit-area for 55 disposing the openings on the grid-area.

To ascertain whether the whirls are produced in the desired degree a sample of the grid intended to be used is placed with its rear side near a flame. On the gas passing 60 through the grid the flaring flame should show a distinctly defined whirling zone at the rear of the grid which merges very suddenly into a slowly moved gas zone.

For the purpose of the invention I have 65 found, that advantageously the width of the openings is to be made as small as it is possible with respect to the material of the grid-sheet, and generally not greater than about 10 mms. A greater speed of flow will generally require a smaller width of mesh.

The total area of the openings of one grid depends upon the speed of the gas flowing 70 through it and should be such that a throttling action or an obstruction of flow is 75 avoided. By increasing the cross sectional area of the casing in comparison with the cross section of the inlet pipe by which the gas is conducted into the casing the speed of flow at the grid can be reduced to any desired extent. It has been found in practice that in most cases the most favorable results are obtained at a speed of one meter per second. At this speed the difference of pressure between the front and rear sides of the 80 grid with slit-shaped openings 1 mm. in width and which occupy about $\frac{1}{3}$ of the grid's surface, corresponds to a pressure of 85 a column of water 1-2 mm. high.

The efficiency of a grid depends largely 90 upon the number of whirl producing edges of the openings present in a unit of surface. For this reason the openings are preferably formed, as above mentioned, in the shape of narrow slits of a width of $\frac{1}{2}$ to 10 mms. arranged parallel to each other.

The free space left behind each grid is sufficient when only giving room for the whirl-zone, the depth of this free space generally depending upon the size of the openings and ranging from 2-10 cms.

A particular advantage of the invention is that a large space is not required for the apparatus as in the known rebounding method by which the mixed gases are forced to pass a relatively large row of rebounding perforated or channeled walls and for this reason the new mixer according to my invention is 105

to be preferred wherever mixers of the ordinary kind would take up too much space.

In the case of gases which attack metal the grid is made from bakelite or similar 5 artificial substances which permit of sharp-edged openings being made therein. The openings are produced by stamping, milling or drilling.

The two gases to be mixed with one another are conducted one to the one side of the grid and the other to the other side of the grid, or two grids may be provided which form between them a mixing chamber, each of the two gases passing through 15 one of the grids into the chamber between the grids. In the first mentioned case the lower pressed or the heavier gas is led immediately into the collecting chamber, the grid being passed only by the higher pressed 20 or the more volatile gas.

The invention is illustrated in the drawing in which

Fig. 1 shows a mixing chamber for mixing two gases with two grids and

25 Fig. 2 a fragment of a grid from the mixer of Fig. 1 in natural size.

The apparatus shown in Fig. 1 consists of a casing in the form of two frustums of a hollow cone connected at their widest parts 30 by a short cylinder, the narrow ends of the frustums having inlet pipes *a*, *b* and the middle cylindrical portion being fitted with a pipe *c* for conducting off the gas mixture. At both ends of the cylindrical portion grids 35 *G*¹, *G*² are placed. The one gas is conducted in through the pipe *a* and the other through the pipe *b*. The passage of the gases through the grids *G*¹, *G*² causes them to form whirls in the cylindrical portion of the casing as 40 indicated by the curved arrows and hereby an intimate mixing of the gases is brought about. The mixture is then drawn off through the pipe *c*.

Each grid *G*¹, *G*² is provided with vertical rows of slits as shown in Fig. 2. The imperforate portion *k* between the slits is about equal in width to the length of a slit, so that the surface area of a row of slits is about equal to the area of the imperforate 50 portion *k* between the rows. The land or unperforated strip may generally be made somewhat wider, say up to 1.5 the width of a row of slits.

It is thus seen that by an appropriate 55 application of the invention apparatus must be constructed by which gases, may be perfectly mixed, in a simple and highly efficient manner.

I claim:

60 1. The art of mixing gases comprising passing at least one of the components of the mixture through a thin grid having small sharp edged openings the smallest diameter of which is substantially ten fold the grid thickness and whose total area is substan-

tially equal to the area of the imperforate portions between the openings, maintaining the speed of the gas low relatively to the size of the openings in the grid to produce a whirling zone of gas immediately behind each grid opening, supplying the second gas to said grid at the rear thereof at a speed not greater than the speed of the first gas and discharging the gas mixture from behind the grid at substantially the induction 75 speed.

2. The art of mixing gases comprising passing each gas through a thin grid into a chamber of which each grid forms a wall, each grid having small sharp edged openings, the smallest dimension of which openings is substantially ten fold the grid thickness, the area of the openings being substantially equal to the adjacent imperforate portions of the grid, maintaining the speed of the gases low relatively to the size of the openings in the grid to produce a whirling zone of gas behind the grid at each opening in which the mixing of the gases takes place and discharging the gas mixture from the 90 chamber at a speed of flow about equal to the induction speed.

3. Apparatus for mixing gases, comprising a vessel having gas inlet and gas outlet pipes, a plurality of thin grids spaced apart 95 to form a mixing chamber and dividing the vessel into separate chambers said grids having a large number of regular openings, the openings having their smallest diameter about ten times the thickness of the grid and the distance apart of such openings being substantially equal to the imperforate adjacent portions of the grid, and each opening having sharp edges, whereby a whirl ring is formed behind the grid at each opening by the sharp edge thereof when gases to be mixed are passed through said vessel at low speed and means to introduce the gases into said mixing chamber through each grid and in opposite directions.

4. Apparatus for mixing gases, comprising a vessel having gas inlet and gas outlet pipes, a plurality of thin spaced grids in the vessel forming a mixing chamber, each grid having a large number of regular openings therethrough whose smallest diameter is about ten times the thickness of the grid and their distance apart substantially equal to their adjacent imperforate portions of substantially equal area and each opening having sharp edges that produce whirl rings in the gas behind the grids at each opening said gases introduced into the mixing chamber from opposite directions.

5. Apparatus for mixing gases, comprising a vessel having inlet and outlet pipes, a plurality of spaced grids inclosing a mixing chamber in the vessel, means for supplying the gases to be mixed to said vessel and passing them through the grids to the cham- 120 125 130

ber from opposite directions, each grid being thin and of about the thickness of drawing paper and having regular openings whose smallest diameter is about ten times the thickness of the grid, the distance apart of such openings being such that the imperforate portions of the grid adjacent the openings are about equal to the area of the openings and each opening has sharp edges that produce behind the grid adjacent each opening a whirl ring in the gas.

6. Apparatus for mixing gases, comprising a vessel, grids dividing the vessel into separate chambers and including between them a mixing compartment, means to supply gas to one chamber and another gas to another chamber for entrance into said compartment in opposite directions, said grid being of about the thickness of drawing paper and having slit-shaped parallel openings whose width is about ten times the thickness of the grid and arranged in rows, the space

between the openings being about equal to the width of an opening and the openings having sharp edges.

7. Apparatus for mixing gases, comprising a vessel traversed by the gases to be mixed, spaced thin grids inclosing a mixing compartment dividing the vessel into chambers and having a thickness of about that of drawing paper, said grid having sharp-edged slit-like parallel openings arranged in rows, said openings having a width about ten times the thickness of the grid and spaced apart about the same distance, the rows being separated by unperforated portions whose width is not less than the width of a row and means to direct gases to said compartment through the grid from different directions.

In testimony whereof I have signed my name to this specification.

ERWIN FALKENTHAL.
